GRAIN SEPARATOR

Leonard Van Domelen and Raymond Van
Domelen, Banks, Oreg.

Application October 4, 1939, Serial No. 297,929

1 Claim. (Cl. 209—240)

This invention relates to grain separators, and has for the primary object the provision of a device of this character which is in the form of an attachment easily adaptable to an elevator of 5 a grain thresher or similar device for receiving therefrom grains of different kinds and which will efficiently and economically separate the different grains from each other and deliver the separated grains for bagging and other modes 10 of collection and which is driven by power derived from the elevator and may be manufactured and sold at a low cost.

With these and other objects in view, the invention consists in certain novel features of construction, combination and arrangement of parts to be hereinafter more fully described and claimed.

For a complete understanding of our invention, reference is to be had to the following 20 description and accompanying drawings, in which—

Figure 1 is a bottom plan view partly in section illustrating a grain separator constructed in accordance with our invention and showing 25 the application thereof to an elevator.

Figure 2 is a vertical sectional view illustrating the device.

Figure 3 is a sectional view taken on the line 3—3 of Figure 2.

30 Figure 4 is a transverse sectional view taken on the line 4—4 of Figure 2.

Figure 5 is a fragmentary plan view illustrating a riddle cleaner.

Figure 6 is a fragmentary end elevation illustrating a portion of one end of the riddle and a portion of one end of a pan.

Referring in detail to the drawings, the numeral 5 indicates a housing of elongated formation and gradually increasing in size toward one 40 end and the largest end thereof is provided with a grain receiving opening 6 adjacent the top wall. The grain receiving opening is arranged in communication with a discharge opening of a grain elevator 7 which may form a part of a 45 threshing machine or similar device (not shown). The elevator 7 includes the usual endless conveyor 8 having buckets 9 thereon which empty as they reach the upper end of the elevator and deposit the grain for passing into the 50 housing 5 or into an inclined platform 10 provided in the housing and projecting slightly into the elevator.

Extending from the top wall of the housing adjacent the opening 6 and above the platform 55 is a deflector plate 11 to deflect grain on the

platform as it is discharged by the buckets of the elevator and also acts to distribute the grain over said platform so that on leaving the latter it will fall onto riddle 12 arranged in the casing 5 for reciprocation and disposed at a slight 5 inclination. The riddle inclines downwardly from the receiving end of the housing and is pivotally supported by links 13 pivoted on walls of the housing and to the riddle. Carried by and underlying the riddle is a pan 14 to receive grain 10 which passes through the riddle and inclines in a direction opposite to the inclination of said riddle and discharges into a hopper 15 located at one end of the housing. The hopper is equipped with diverging discharge spouts 16. 15

At the opposite end of the housing is a hopper 17 to receive grain which passes from the lower end of the riddle and is provided with diverging discharge spouts 18.

The riddle 12 consists of a frame 19 closed by 20 a screen 20, the mesh of which may be of any desired gauge depending on the character of seeds that are to be separated. The uppermost end of the frame 19 has connecting links 21 pivoted thereto which extend through slots 23 in 25 the end wall of the housing 5 and are journaled on cranks 24 of a crank shaft 25 supported by journals 26 at one end of said housing 5. The crank shaft has secured thereto a sprocket gear 27 over which is trained an endless sprocket 30 chain 28 which in turn passes about a sprocket gear 29 secured on the uppermost shaft 30 of the conveyor 8 of the elevator 7, so that when the conveyor of the elevator is in operation the riddle 12 will receive a reciprocal motion. 35

A clearer frame 31 is arranged directly under the riddle frame 19 and spaced therefrom and carries relatively spaced transversely arranged supporting bars 32 on which are secured strips of fibre such as belting, felt or any other suitable material. The strips are indicated by the character 33 and the upper edges thereof rub against the screen 20 for the purpose of maintaining the screen clean during the use of the device. The screen 20 rubs over the cleaning elements 33 during the reciprocation of the riddle and as the cleaning construction of the device is of skeleton formation seeds passing through the screen 20 may readily pass through the cleaner onto the bottom wall of the casing for 45 gravitation into the hopper 15.

It is preferable that one of the side walls of the housing 5 be equipped with a door 34 which may be readily opened to give inspection to the riddle while in operation or to permit the easy 55

removal of the riddle of the housing when desiring to change for another wherein the screen will be of a different gauge mesh.

In operation, the different kinds of grain discharged from the elevator 7 are received on the platform 10 and gravitate therefrom onto the riddle, the larger seeds passing off the lower end of the riddle into the hopper 17 while the smaller grain or seeds pass through the screen onto the pan 14 and gravitate therefrom into the hopper 15, thereby bringing about a quick and efficient separation of grain or seeds of different kinds.

It is a common practice to grow within a field different kinds of seeds or grain such as oats and peas and to thresh them simultaneously. When this threshing operation is carried on the present invention or separator as heretofore described and shown in the drawings will efficiently separate the peas from the oats, the peas passing into the hopper 17 while the oats pass into the hopper 15. The different kinds of grains or seeds from their respective hoppers can be easily bagged or otherwise collected from the chutes of said hoppers.

It is believed that the foregoing description, when taken in connection with the drawings will fully set forth the construction and advan-

tages of this invention to those skilled in the art to which such a device relates so that further detailed description will not be required.

What we claim is:

In a grain separator, a housing having the bottom thereof open and provided with a grain receiving opening in one end thereof and adjacent the top wall of said housing to admit grain from a thresher, an inclined platform supported by said housing and extending inwardly thereof from the grain receiving opening, hoppers mounted in the open portion of the housing and each including discharge means, a pan slidably supported by the hoppers and inclined toward one of said hoppers at one end thereof so as to dump into said hopper and the other end of said pan including an upstanding wall to prevent the pan from dumping in the other hopper, an inclined reciprocally mounted riddle in the housing and located over the pan and having one end hinged on the upstanding wall of said pan and having the other end thereof disposed under and beyond the free end of the platform, and a cleaner of skeleton formation contacting the riddle and located between the latter and the pan and secured on the housing.
